Inventor
Andrew R. McCaffrey.

By Howard Ed Parlow
Attorney.

UNITED STATES PATENT OFFICE.

ANDREW A. McCAFFREY, OF PROVIDENCE, RHODE ISLAND.

GARMENT-HANGER.

1,336,849.

Specification of Letters Patent. Patented Apr. 13, 1920.

Application filed February 24, 1920. Serial No. 360,689.

To all whom it may concern:

Be it known that I, ANDREW A. McCAFFREY, a citizen of the United States, and resident of the city of Providence, in the county 5 of Providence and State of Rhode Island, have invented certain new and useful Improvements in Garment-Hangers, of which the following is a specification.

This invention relates to garment hangers, and has for its object to provide a hanger of simple and practical construction, which is adapted to support a waist or coat and a skirt or the device may be employed for supporting a jacket and trousers and 15 other garments, if desired.

The nature and advantages of the invention will be better understood when the following detail description is taken in connection with the accompanying drawings, the 20 invention residing in the combination and arrangement of parts as claimed.

In the drawings forming part of this specification like numerals of reference indicate similar parts in the several views and 25 wherein:

Figure 1 is a sectional side elevation of one form of my improved hanger which is shown as being adapted more particularly for supporting a coat or waist and skirt.

30 Fig. 2 is a sectional side elevation of a modified form of device more particularly adapted for supporting a coat and trousers or other garment.

Fig. 3 is a sectional end view on line 3—3 35 of Fig. 1.

Fig. 4 is a sectional end view on line 4—4 of Fig. 2.

Fig. 5 is a perspective view of one of the 40 garment-engaging members which is adapted to be slidably mounted within the tubular bar.

With reference to the drawings, 10 designates the bar-member of my improved hanger, which is constructed of a tube, the 45 same being cut to the desired length and bent on an arc of a circle so as to receive and properly support the shoulder portions of a coat or waist. The inner or under side of this tube is slotted as at 11.

50 Mounted within and at each end of this tubular bar is a garment-engaging member which is formed with a body portion 12 of wire. At the opposite ends 13 and 14 of this body portion the wire is bent into a coil 55 form, the wire from coil 14 extending out

through the slot 11 and downwardly forming a garment-engaging arm 15, while the wire from coil 13 also extends outwardly through the slot 14 but is curved to form a handle or operating member 16 adapted to 60 be engaged by the hand of the user for the purpose of drawing these members which are mounted in opposite ends of the tube toward each other against the tension of the compression springs 17, which spring is also mounted within the tube 10, its ends engaging the coils 13 of the said opposite garment-engaging members.

Plugs 18 may be fixed into opposite ends of the tube to close the same and also to serve as abutments or stops against which the garment-engaging members are normally pressed by action of the spring 17.

In order to provide simple and effective means for supporting this garment holder, I have provided a wire hook 19, the body portion of which extends through the tube and may be secured therein by a pin 20 or otherwise; the lower end of this hook body may also extend through the tube and be 80 provided with a second or lower hook 21 which may also be employed for supporting other wearing apparel.

In some instances, as illustrated in Fig. 2, I may omit the skirt-supporting arms 15 85 and attach clasps 22 to the operating arms 16 if desired, to facilitate the engagement of these arms with garments.

These arms 15 also may be bent or curved slightly as at 23 to also serve as handles for 90 positioning the clasps to engage the garment.

My improved garment hanger is very simple, practical and inexpensive in construction and effective in its operation and by its use a number of garments may be supported and held in desired position, and by its construction the hanger is rendered very strong and durable and light in weight.

The foregoing description is directed solely toward the construction illustrated, but I desire it to be understood that I reserve the privilege of restoring to all the mechanical changes to which the device is susceptible, the invention being defined and limited only by the terms of the appended claims.

I claim:

1. A garment hanger comprising a tubular bar curved to receive and support the 110

shoulder portions of a garment, said tube being slotted on its under side for a portion of its length on each side of its center, garment-engaging members slidably mounted in opposite ends of said tube, each being provided with an arm extending through one of said slots, a spring in said tube pressing said members apart, and means whereby said members may be engaged to be drawn toward each other against spring pressure to receive the garment.

2. A garment hanger comprising a tubular bar curved to receive and support the shoulder portions of a garment and slotted on its under side, a member slidably mounted in each end of said tube and provided with a garment-engaging arm at one end extending out through its adjacent slot, said members being each also provided with a finger grip operating portion at its oppo-

site ends also extending through said slots, and a spring in said tube for pressing said members apart.

3. A garment hanger comprising a tubular bar curved to receive and support the shoulder portions of a garment and slotted on its under side, stop members at the ends of said tube, a member slidably mounted in each end of said tube, a spring in said tube for normally pressing each of said members outwardly against its stop, an arm on each of said members extending through its slot to engage a garment between them, said arms being adapted to be moved to compress said spring upon being positioned to engage a garment, and means on said bar by which the whole may be supported.

In testimony whereof I affix my signature.

ANDREW A. McCAFFREY.
